MEANS FOR AGITATING LIQUIDS

Hans Leopold Simon, London, England

Application July 25, 1950, Serial No. 175,800
In Great Britain July 26, 1949

3 Claims. (Cl. 259—101)

1

The present invention relates to means for agitating liquids and has for an object to provide an improved portable agitator for liquids which is inexpensive, easily positioned, and adapted for use with various kinds of liquid containers.

Removable agitators for domestic washing machines are known but such agitators are adapted for use in a specifically designed tank or receptacle usually having an upstanding column or the like in which the agitator seats. The column is usually positioned centrally of the tank although in one known construction the column is located outside the tank and connected thereto by suitable pipes or ducts. In these known constructions means are usually provided for maintaining the articles immersed in the liquid contained in the tank free from the inlet and/or outlet of the agitator, which means are incorporated in the tank construction proper and do not form part of the removable agitator.

Portable agitators are also known which are adapted for use in any suitable container but such agitators are not shielded from contact with articles which may be immersed in the liquid in the container and consequently the liquid immediately surrounding the agitator is not maintained free from obstruction by such articles.

Furthermore in known agitators the liquid is agitated either by means of a continuously rotating paddle or other form of blade which is submerged in the liquid, or the liquid is agitated by means of a paddle which is adapted to be reciprocated and which is positioned to lie just below the level of the liquid. It has been found that in most of these types of agitators there is in fact only a local disturbance of the liquid in the one case to produce a continuous current through that liquid and in the other case to produce a to and fro agitation in the top layer of liquid. When such agitators are used for washing clothing reliance is placed upon the actual movement of the clothing in the liquid to break up the current or the upper agitation to distribute the liquid through the clothing. In yet another known form of agitator the clothing is placed inside a drum which is wholly or partially immersed in the liquid and the drum rotated, this rotation being relied upon to produce circulation of the liquid through the clothing in the drum the rotation of the drum also serving to turn the clothing over.

According to the present invention a portable device for agitating liquids in a container comprises means for producing a directed flow of

2

liquid throughout the container, said means being adapted to operate in a volume of the liquid defined by a perforated casing surrounding and spaced from said means and extending upwardly a substantial distance from the bottom of the device, the arrangement being such that the liquid is agitated throughout substantially the whole depth thereof.

Conveniently the liquid agitating means are enclosed by an open mesh screen or the like through which the liquid in which the device is immersed may easily flow, the said means being actuated by an electric motor mounted above the screen, and the device being adapted to be positioned so that it lies close to a wall of the container for said liquid, the agitating means, screen and electric motor forming a single and readily removable assembly.

In one form of construction of a device according to the invention the liquid agitating means comprises a vertically disposed blade oscillating about a vertical axis, while in a further construction, the agitating means comprises an uplift tube having inlet and outlet openings and having mounted therein a rotary impeller for drawing in liquid through the inlet openings and discharging it through the outlet openings.

The invention will now be described with reference to the accompanying drawings in which:

Figure 1 is a front elevation of a device according to the invention having an oscillating blade type of liquid agitator, part of the casing being cut away to show details of construction;

Figure 2 is a plan view of the device of Figure 1 also having part of the cover cut away;

Figure 3 is a section taken along the line III—III to Figure 1;

Figure 4 is a side elevation partly in section of the device shown in Figure 1 but fitted with an uplift tube type of liquid agitator;

Figure 5 is a sectional view of a container showing the manner in which the device may be positioned therein; and

Figure 6 is a side elevation partly in section showing an alternative construction of the device with an uplift tube.

Referring to Figures 1, 2 and 3 a device according to the invention comprises a base plate 1 upon which is mounted an electric motor 2. Rotatably mounted in the base plate 1 and extending downwardly therefrom is a vertical shaft 3 having secured thereto an agitator blade 4 which is caused to oscillate to and fro from the position shown in full lines (Figure 3) to the position shown in chain dotted lines. Os-

cillation of the shaft 3 may be produced by any suitable means and as shown the shaft 3 has mounted on the upper end thereof a crank 5 to which is connected one end of an arcuate link member 6 by means of a crank pin 7. The other end of the link member 6 is connected to a crank 8 by means of a crank-pin 9 the crank 8 being mounted on the lower end of a vertical spindle 10 having a gear wheel 11 in engagement with a worm 12 mounted on one end of the motor shaft 13. Rotation of the motor shaft is translated through the link and crank mechanism into an oscillating movement of the shaft 3 about its longitudinal axis whereby the blade 4 is caused to move to and fro between the extreme positions shown in Figure 3.

Secured to the base plate 1 as by screws 14 for example is a downwardly depending cage 15 conforming to the contour of the base plate and extending a short distance below the lower edge of the blade 4. The cage 15 is constructed of wires or rods 16 forming a screen the meshes of which are sufficiently large to enable easy flow of liquid to and from the agitator blade but serve to keep large solids such as articles of clothing for example clear of said blade. The wall of the cage is strengthened by a plate 17 extending the length thereof and forming that portion of the wall lying to the rear of the shaft 3. Secured to the plate 17 as by welding for example is a strip 18 extending slightly above the base plate 1 and having secured thereto a U-shaped spring member 19 to the free end of which is secured a curved rod or bar 20. A detachable cover 21 is adapted to fit on the base plate and encloses the motor 2 and the link mechanism. A suitable aperture 22 is provided in the cover through which passes a flexible connection 23 for connecting the electric motor to any suitable source of electric power.

In the construction shown in Figure 4 the blade type liquid agitator of Figure 1 has been replaced by an uplift tube type of agitator. In this construction, the motor 2 is mounted vertically upon the base plate 1 which supports an uplift tube 25 extending downwardly within the cage 15. The motor shaft is provided with an extension 26 extending downwardly centrally of the tube 25 and support in a bearing 27 mounted on a closure plate 28 of the tube 25. Near the lower end of the tube 25 are a number of inlet openings 29 spaced around the periphery of the tube while in the upper portion of the tube there is provided a single outlet 30 facing outwardly from the rear plate 17. Impeller blades 31 are mounted on the shaft 26 and are adapted to draw the liquid in through the inlet openings 29 and discharge it through the outlet 30. In order to improve the efficiency of the agitator, the rising liquid in the tube 25 is directed towards the outlet 30 by a flared baffle 32 extending across the tube and having mounted therein an additional bearing 33 for the shaft 26.

Figure 5 illustrates the manner in which the device is secured in position in a cylindrical container 24 (shown in cross section). From this figure it will be seen that the wall of the container is gripped between the curved rod 20 and the strip 18 thereby supporting the agitator in a vertical position in contact with the wall. In use it is preferred for the device to rest on the bottom of the vessel or other container in which it works the U-shaped member 19 serving to hold the device close to the wall of the container. Conveniently the U-shaped member 19 may be mounted to slide vertically with respect to the

cage 15 so that the device may be accommodated in containers of varying depth.

In this manner the device is securely and firmly held in the correct position in the container but may be easily and quickly lifted out and inserted in another container.

The invention is not limited to the above described embodiments thereof and the device may be adapted to stand in the centre of a container. Similarly the uplift tube may be provided with more than one outlet distributed around the periphery thereof, the baffle 32 then taking the form of an inverted cone.

Thus in Figure 6 there is shown a further construction of a liquid agitating device according to the invention which device is adapted for positioning centrally of the tank or container in which it is used. As will be seen from the drawing, the device comprises a base plate 40 adapted to rest on the bottom of the tank or container, an uplift tube 41 which is flared at its upper end as at 42, a baffle 43 and a skirted wire mesh cylinder 44 all of which are clamped in position by means of rods 45 screw threaded at each end, which rods are screwed into holes 46 in an annular boss 47 formed on the base 40 and receive at their other ends a nut 48, by means of which the assembly is clamped together. Annular distance pieces 49 surround the rods 45 between the end of the tube 41 and the baffle 43 to provide an annular space 50 which constitutes the outlet for the liquid forced upwardly through the tube by means of an impeller 51, the liquid entering the tube through inlet openings 52 positioned adjacent the lower end of the tube and spaced around the periphery thereof. The annular boss 47 is grooved as at 53 to receive the lower end of the tube 41 and the base plate and the lip 54 of the tube have formed in them circumferential grooves 55 and 56 respectively adapted to receive the end of the wire mesh cylinder 44.

Also secured to the upper ends of rods 45 and clamped against the baffle 43 are inwardly extending supporting members 57 adapted to support an electric motor 58 in a vertical position centrally of the base 40. The members are secured to the motor by means of bolts 59.

The motor 58 drives a vertical shaft 60 journalled in a bearing 61 formed in the baffle 43 and a bearing 62 supported by the base plate 40, the impeller 51 being secured to the shaft at a point immediately above the inlet openings 52.

The baffle 43 is formed with an upstanding rim 63 to which a cover 64 is secured by means of screws 65.

In operation, the device is placed in a tank or container preferably centrally thereof and the liquid is drawn in through the inlet openings 52 by means of the impeller 51 driven by the motor 58, and discharged through the annular outlet 50, the baffle 43 serving to direct the liquid to the outlet. The wire mesh cylinder 44 defines a volume of liquid surrounding the tube 41 which liquid is acted upon by the impeller 51.

The device may also be constructed so as to permit adjustment in height or width or both so as to be accommodated in containers of various sizes and may be provided with any form of liquid agitator which will give a directed flow of the liquid throughout the container.

What I claim is:

1. A portable device adapted to be removably positioned in a container for agitating liquids contained therein comprising means for produc-

ing a uniformly directed flow of liquid in the container, said means being adapted to operate in an unobstructed volume of the liquid defined by a perforated casing surrounding and spaced from said means and extending upwardly a substantial distance from the bottom of the device whereby the liquid is agitated throughout substantially the whole depth thereof, said means comprises a blade extending longitudinally of the device and adapted to be oscillated about one longitudinal edge thereof.

2. A device according to claim 1 wherein said blade extends radially from a shaft disposed longitudinally of the device and means are provided for connecting the shaft to an electric motor mounted in the device whereby the motor imparts an oscillatory movement to the shaft about its axis.

3. Portable liquid agitating apparatus adapted to be removably positioned in a container and comprising, in combination, liquid moving means for producing a uniformly directed flow of liquid in the container; and screen means fixedly mounted with respect to said liquid moving means, said screen means surrounding and being spaced from said liquid moving means to define

5

an unobstructed volume of liquid in which the said liquid moving means operates, whereby liquid moved by said liquid moving means may pass freely through said screen means while the latter prevents any objects in the liquid in the container from contacting said liquid moving means, said liquid moving means comprising a motor, a shaft, linkage means interconnecting said motor and shaft for oscillating the latter, a blade having opposite edge portions one of which is fixedly connected to said shaft and the other of which is located adjacent to said screen means.

HANS LEOPOLD SIMON.
